UNITED STATES PATENT OFFICE.

EDWARD W. BURGESS, OF MILWAUKEE, WISCONSIN, ASSIGNOR TO INTERNATIONAL HARVESTER COMPANY, OF CHICAGO, ILLINOIS, A CORPORATION OF NEW JERSEY.

CORN-HARVESTER FRAME.

SPECIFICATION forming part of Letters Patent No. 727,082, dated May 5, 1903.

Application filed June 9, 1902. Serial No. 110,768. (No model.)

To all whom it may concern:

Be it known that I, EDWARD W. BURGESS, a citizen of the United States, residing at Milwaukee, in the county of Milwaukee and State 5 of Wisconsin, have invented certain new and useful Improvements in Corn-Harvester Frames, of which the following is a specification, reference being had to the accompanying drawings, forming a part thereof.

10 My invention relates to improvements in corn-harvester frames in which two carrying-wheels are employed to support it and in which gathering-sills are located upon opposite sides of a corn-passage; and the objects 15 of my improvement are, first, to provide a frame simple in construction and composed of few parts; second, to construct a frame strong and durable to resist the heavy strain to which this class of machinery is often subjected. I attain these objects by the construction illustrated in the accompanying drawings, in which—

Figure 1 is a plan view of the frame, and Fig. 2 is an end elevation.

25 Like numerals refer to like parts throughout both views.

1 and 2 are gathering-sill pieces positioned on opposite sides of the corn-passage 3. These sills extend forward and are bent outward at 30 their front ends, forming a flaring receiving passage-way for the corn. The gathering-sills 1 and 2 are braced laterally by subsills 4 and 5. A transverse tubular sill 6 extends across the sills 4 and 1 forward of the drive-wheel 7 and extending beyond the drive-wheel on the stubbleward side of the machine has the tongue 8 pivoted thereon, and a combined seat-spring socket and foot-rest 9 is secured thereto outside of the tongue. 10 is 35 the seat-spring, and 11 the seat. A tongue-brace 12 is secured at its forward end to the tongue 8 and at its rear end to a sleeve 13, rotatable on the sill 6 between the longitudinal sills 1 and 4. A brace 14 is secured at 40 the seat-spring, and 11 the seat. A tongue-brace 12 is secured at its forward end to the tongue 8 and at its rear end to a sleeve 13, rotatable on the sill 6 between the longitudinal sills 1 and 4. A brace 14 is secured at 45 its rear end to the sill 6, near the tongue attachment 15, and at its forward end to the sill 4.

4. A transverse sill 16 extends across the rear ends of the sills 1, 2, 4, and 5 and is secured thereto. It extends grainward of the 50 sill 5, and a grain-wheel-supporting arm 17

is journaled thereon. The supporting-arm has the axle 18 on its front end, on which is the grain-wheel 19. Between the transverse sills 6 and 16 is the transverse sill 20, also of tubular form, extending across sills 1, 2, 4, 55 and 5 and secured thereto.

21 is a longitudinal tubular sill parallel with, adjacent to, and inside the drive-wheel 7 and extending rearward beyond the stubbleward end of the sill 16. 60

22 is an intermediate longitudinal tubular sill extending from the stubbleward end of sill 20 to sill 6, parallel with and adjacent to but nearer the vertical plane of the drive-wheel than the sill 21. A joint-plate 23 receives the meeting ends of the sills 20, 21, and 22 and is secured thereto. A joint-plate 24 is secured to the sill 6 and receives the forward end of sill 22. 65

25 is a gear-frame secured to the sills 16 and 21, and a radius-arm 26 is journaled on its stubbleward end 27 and carries the axle 28 of the drive-wheel 7. 70

A main frame constructed in this manner is strong, light, and compact, and being between the two supporting-wheels they can be easily attached or detached. 75

I do not herein claim the manner of supporting and adjusting the platform on the carrying-wheels, as the same forms the subject-matter of and is claimed in my application, Serial No. 110,765, filed June 9, 1902. 80

What I claim as my invention, and desire to secure by Letters Patent, is—

1. In a corn-harvester, the combination of the frame, and the supporting-wheels located at opposite sides of and outside of said frame, said frame comprising a pair of forwardly-projecting gathering-sills, a forwardly-projecting bracing-sill at the side of each gathering-sill, a longitudinal sill extending along the inner side of the drive-wheel, and transverse sills 16 and 20 connecting the gathering and bracing sills together and to the longitudinal sill, all of said sills lying wholly between the wheels. 85 90

2. In a corn-harvester, the combination of the frame, the driver's seat, and the supporting-wheels located at opposite sides of and outside of the frame, said frame comprising 95 100

a pair of forwardly-projecting gathering-sills, a forwardly-projecting bracing-sill at the side of each gathering-sill, a longitudinal sill extending forward alongside of and to a point in front of the drive-wheel, and a cross-sill connecting the forward part of the stubble-ward gathering and bracing sills with said longitudinal sill, said cross-sill extending stubbleward in front of the main wheel and forming a support for the driver's seat.

3. In a corn-harvester, the combination of the frame, the tongue, a tongue-brace, and the supporting-wheels located at opposite sides of and outside of said frame, said frame comprising a pair of forwardly-projecting gathering-sills, a forwardly-projecting bracing-sill at the side of each gathering-sill, a longitudinal sill extending forward alongside of and to a point in front of the drive-wheel, and a cross-sill one end of which extends grainward and connects the forward part of the stubbleward gathering and bracing sills, and to which the tongue-brace is pivotally connected, and the other end of which sill extends stubbleward in front of the drive-wheel and forms a pivotal support for the rear end of the tongue.

4. In a corn-harvester, the combination of the frame, and the supporting-wheels located at opposite sides of and outside of said frame, said frame comprising a pair of forwardly-

projecting gathering-sills, a forwardly-projecting bracing-sill at the side of each gathering-sill, the transverse sills 16 and 20 connecting the gathering and bracing sills together, said transverse sills lying wholly between the wheels, the said sill 16 being extended grainward beyond the outermost bracing-sill and forming a pivotal support for the arm carrying the supporting-wheel on that side of the machine.

5. In a corn-harvester, the combination of the frame, and the supporting-wheels located at opposite sides of and outside of said frame, said frame comprising forwardly-projecting gathering and bracing sills, transverse sills 16 and 20 connecting the rear ends of the gathering and bracing sills together, a longitudinal sill extending rearward alongside of the driving wheel beyond the rear cross-sill 50 16, and another longitudinal sill extending forward from the cross-sill alongside of and to a point in front of the drive-wheel, and a front cross-sill 6 connecting it to the stubble-ward gathering and bracing sills.

In witness whereof I hereto affix my signature in presence of two witnesses.

EDWARD W. BURGESS.
